GRAIN ABRADING AND CLEANING APPARATUS

Lawrence E. Egedal, Milwaukee, Wis.

Application December 15, 1944, Serial No. 568,271

7 Claims. (CL. 146—261)

1

The present invention relates to apparatus for milling grain and other materials, and more particularly to grain abrading and cleaning apparatus.

An object of the invention is to provide an improved grain milling apparatus for efficiently scouring and cleaning grain.

Another object is to provide a grain milling apparatus including simple but effective fanning and screening means cooperating with abrading means for the grain.

A further object is to provide a grain milling apparatus which is of relatively inexpensive and durable construction.

The invention further consists in the several features hereinafter described and claimed.

In the accompanying drawings, illustrating certain embodiments of the invention,

Fig. 1 is a side elevation of a grain processing machine constructed in accordance with the invention;

Fig. 2 is a detail sectional plan view taken generally on the line 2—2 of Fig. 1;

Fig. 3 is a sectional elevation taken generally on the line 3—3 of Fig. 1 and showing the machine arranged for grain scouring and cleaning;

Fig. 4 is a detail sectional elevation taken on the same plane as Fig. 3 and showing abrading means of the machine on an enlarged scale;

Fig. 5 is a bottom view of the abrading rotor and housing;

Fig. 6 is a bottom view of the abrading stator;

Fig. 7 is a detail elevation of a screening member and its mounting, parts of the latter being shown in section; and

Fig. 8 is a detail sectional elevation of a modified form of abrading stator.

In these drawings, 20 designates a legged frame or support here shown to be formed of metal tubing and mounted on casters 21. The frame includes upper and lower pairs of parallel horizontal bars 22 and 23, the upper bars 22 being connected by a pair of parallel cross bars 24, and the lower bars 23 being connected by a pair of parallel cross bars 25.

A housing 26, preferably in the form of an inverted cup, includes a horizontal top wall 27 and a downwardly projecting cylindrical side wall or skirt 28, the latter preferably having a bead 29 at its lower edge and a bead 30 around its upper portion. The housing top wall 27 extends below the cross bars 24 and is rigidly secured thereto by screws 31. At its upper side the housing top wall 27 is provided with a central embossment 32 extending upwardly between the cross bars 24 and having a downwardly converging conical seat 33 on which is rigidly mounted the conically formed bottom wall 34 of a hopper member 35. The hopper member is adapted to hold grain or other granular material.

2

An electric motor 36 extends centrally within the hopper and has a vertical shaft 37, the projecting lower end of which extends downwardly through a central aperture 38 in the housing embossment 32. The motor frame is provided with supporting legs 39 which are rigidly secured to the housing by screws 40, the bottom wall 34 of the hopper being clamped between the housing and the motor-supporting legs.

10 In the embodiment of the invention shown in Figs. 3 to 7, constituting a grain scourer and cleaner, a mill stator, designated as a whole by the numeral 41, is detachably and adjustably secured to the underside of the housing top wall 27. The stator comprises a disk-like abrasive member or stone 42 having a downwardly projecting peripheral flange 43 and a flat disk-shaped web 44, the latter being firmly clamped between a disk-like metal top member 45 and a metal bottom member 46 of skeleton or spider form, these members being drawn together by screws 47. If desired, the abrasive member may also be cemented to one or both of the clamping members. The bottom member 46 has a central cylindrical shell 48, the upper edge of which fits in a shallow circular recess 49 formed in the lower face of the housing top wall 27 to center the stator. The stator is secured to the housing top wall 27 by screws 50 which are seated in the stator plate member 45 and pass through vertically adjustable bushings 51 screwed through the housing wall, the lower ends of the bushings bearing on the plate member 45, and the screws carrying respective lock nuts 52 bearing on the upper ends of the bushings. The clamping member 46 has at its underside a series of concentrically arranged ribs 53 forming annular grain channels 54 between them. If desired, these grain channels may have abrasive surfaces. Each 20 rib has a gap 55 to permit the outward passage of grain. Preferably, the several gaps are arranged approximately in line at one side of the clamping member, as shown in Fig. 6. The peripheral flange 43 of the abrasive member 42 is continuous and presents a relatively wide flat grinding land 56 which is operative when the machine is used as a flour mill, as hereinafter described. The stator is concentrically disposed in the housing 26 and has its periphery spaced inwardly from the cylindrical skirt 28 of the housing.

45 A rotatable centrally apertured abrasive member or stone 57, preferably in the form of a disk, lies centrally below the ribbed stator and is sufficiently close to the lower edges of the ribs 53 to prevent the passage of grain under the ribs. The abrasive member 57 is carried on a metal disk 58 to which it is rigidly secured, as by cementing. The metal disk is here shown to have 50 a peripheral flange 59 for radially confining the

abrasive member. The metal disk 58 has a central bore 60 which fits on the reduced shoulder-forming screw-threaded lower end portion 61 of the motor shaft 37. A disk nut 62 on the motor shaft clamps the disk 58 in place and is secured to the disk as by screws 63. In addition to the disk nut 62, a lock nut 64 may be screwed onto the motor shaft.

The rotary abrasive disk and its metal supporting disk are provided with a plurality of spaced openings 65 which register with the outermost grain channel 54 to permit the scoured grain kernels and debris to pass downwardly out of the scouring rotor. Some of the finer debris will also find its way outwardly through the peripheral slit or gap 66 formed between the stator and the rotor. The lower surface of the rotor disk 58 has a vanned fan-forming disk 67 detachably secured thereto as by screws 68. The lower surface of the disk nut 62 has a smaller fan 69 detachably secured thereto by screws 70.

Removably resting on the lower bars 23 and 25 of the frame is an annular receptacle 71 of cylindrical shape having inner and outer cylindrical walls 72 and 73, respectively, the inner wall forming a central vertical tube open at both ends, and the upper edge of the outer wall having an outwardly beaded 74. The upper portion of the tube-forming inner wall has one or more vertical slots 75 and is contractible by eared bands 76 secured to this wall and carrying clamping screws 77. The receptacle 71 is suitably centered below the housing 26, as by means of short positioning pegs 78 which project upwardly from the frame bars 23.

A sieve or screen member of wire cloth or perforated sheet metal comprises a cylindrical upper portion 79 and a downwardly converging conical lower portion 80. The sieve is rigidly carried on a metal tube 81 which slidably fits in the contractible receptacle tube 72 and is clamped to the latter tube at an adjustable elevation. The sieve is of rather coarse mesh which, however, is sufficiently small to prevent passage therethrough of cleaned grain kernels. The cylindrical portion 79 of the sieve extends concentrically in the housing into the space between the housing skirt 28 and the periphery of the mill stator 41. The upper edge of the cylindrical portion 79 is spaced a short distance from the underside of the housing top wall, and is here shown to carry peripherally spaced stop projections 82 to gauge this distance, thus presenting a series of slots along the upper edge of the sieve.

An annular filter-forming cover or casing 83 of porous cloth, such as flannel, and preferably of downwardly converging conical or conoidal shape, extends loosely between the housing 26 and the outer wall of the receptacle 71 and has elastic edge portions detachably secured to the peripheral bead 30 of the housing and the peripheral bead 74 of the receptacle. The cover is thus supported at its upper and lower edges. The porous cloth cover permits the passage of air therethrough, but prevents escape of fine dust or flour.

The vertical tube 72 of the receptacle forms a passage for an upward current of air, as indicated by arrows in Fig. 3, and also provides a conduit for the descent therethrough of cleaned grain kernels which are caught in a container 84 of any convenient size set on the floor below the tube.

In setting up the machine for use as a grain scourer, the sieve 79, 80 is lowered to the broken line position of Fig. 3 before the receptacle 71 is

placed in position on the frame bars 23 and 25, thus permitting the upper edge of the sieve to clear the lower edge of the housing skirt 28. The cover 83 is placed around the receptacle before the sieve is raised and fastened in its operative position, and the cover is then applied to the supporting bead 30 of the housing. The stop projections 82 on the upper edge of the sieve determine the normal gap between this edge and the lower face of the housing top wall 21, but this gap can be adjusted to a greater distance by vertically adjusting the metal tube 81 which carries the sieve.

In the operation of the machine as a scourer and cleaner, a quantity of wheat or other granular material is placed in the hopper 35, and the motor 36 is set in rotation, driving the rotary abrasive member 57 at a high speed, for example a peripheral speed of 10,000 feet per minute. The grain descends from the hopper through the aperture 38 and passes through the central chamber of the ribbed stator onto the rotary abrasive disk 57. The grain kernels are abraded by the rotary disk 57, removing fuzz and dirt from the kernels and also removing the woody outer portions of the kernels. The high-speed rotary disk 57 has a light contact with the kernels, and removes the dust-laden outer coating of the kernels without danger of cracking the kernels. The ribs 53 of the stator retard the outward passage of the kernels and also have some abrading action. The grain kernels travel around the channels 54 of the stator under urge of the rotating disk and pass from each channel to the next outer channel through the gap 55 in the rib between the channels, as indicated by arrows in Fig. 6. Some of the grain may make more than one circuit in each channel before passing to the next channel. Any desired distribution of the grain within the channels can be obtained by selecting the width of the channels and the width and location of the rib gaps 55. The grain kernels finally reach the outermost channel and are discharged downwardly through the openings 65 in the rotor. The discharged kernels are swept around the sieve 79, 80 by air currents to cause a further abrading action. The air currents are produced mainly by the rotating fans 67 and 69 which draw air upwardly through the central tube 72 of the receptacle and cause movement of the air in the direction indicated by arrows in addition to a swirling or rotary action about the vertical axis of the sieve. The rotation of the rotor may also draw some air down through the mass of grain in the hopper and discharge it from the peripheral region of the rotor. In some instances, there may be an inward and upward passage of air through the lower portion of the sieve 80, as indicated by arrows in Fig. 3. The fuzz, dirt, and other fine removed material discharged from the rotor pass outwardly through the sieve meshes and fall into the receptacle 71, while the cleaned grain kernels fall through the tube 72 and into the container 84. The passage of the kernels along the sieve walls aids in keeping the meshes open. Any sticks, straws, joints, and other light foreign objects in the grain which do not or can not pass through the sieve meshes will be swept upwardly within the sieve and blown out over the top edge of the sieve so that they will be deposited in the receptacle 71. By changing the size or number of the fan blades, any desired degree of buoyant separation can be obtained.

A slight air pressure existing within the filter cover 83 causes the cover to belly out, as shown

in Fig. 3, and air currents serve to cause a fluttering or agitation of the cover, preventing accumulation of fines on the inner surface of the cover.

When the receptacle 71 is to be removed from the machine, the cover 83 is detached from the housing and the sieve 79, 80 is lowered, thus permitting lateral withdrawal of the receptacle.

In the modified form of mill stator 41' shown in Fig. 8, the abrasive member 42' has a number of annular ribs 53' formed thereon, as by molding, and the clamping member 46' is of smaller diameter than the clamping member 46 of Fig. 4. The stator of Fig. 8 is otherwise the same as that of Fig. 4 and is used in the same manner, the several ribs having gaps for the outward passage of grain.

The bottom edge of the skirt 28 of the housing has an inturned flange or rib 93 which serves to deflect particles of descending material inwardly. The cylindrical sieve portion 79 has an annular baffle 94 near its lower end to direct light coarse particles inwardly to the zone of action of the disintegrating fans.

While the machine of the invention is more particularly intended for use in the processing of grain, it is also capable of use in the treatment of other materials.

What I claim as new and desire to secure by Letters Patent is:

1. A device of the character described, comprising a housing having a top wall and a downwardly projecting annular skirt, grain-scouring means including an abrasive rotor within said skirt and rotatable on a generally vertical axis, there being a grain discharge outlet from said rotor, a sieve extending around said rotor and having its upper edge adjacent to said top wall, there being a slot-like passage between said sieve upper edge and said top wall to admit light foreign objects discharged with the scoured grain, said passage being larger than the sieve meshes, and a grain conduit at the lower end of said sieve for downward passage of scoured grain.

2. A device of the character described, comprising grain-scouring means including an abrasive rotor rotatable on a generally vertical axis and from which scoured grain is discharged, a tubular sieve extending around said rotor in outwardly spaced relation thereto, a vertical tubular support, a tubular member secured to the lower end of said sieve and telescopically related to said support to permit vertical shifting of said sieve for varying the elevation of the said sieve, and means for securing said tubular member on said tubular support in vertically adjusted position.

3. A device of the character described, comprising a housing having an annular imperforate skirt, the lower portion of which has an inwardly projecting rib, a sieve secured to said housing and projecting downwardly from said skirt below said rib, means for introducing material to be sifted into the region within said skirt, and means for producing air currents within said sieve, said rib guarding said sieve from impact of rapidly moving particles of material passing downwardly within said skirt.

4. A device of the character described, comprising a housing having an annular imperforate skirt the lower portion of which has an inwardly projecting rib, a sieve secured to said housing and

projecting downwardly from the skirt below said rib, means for introducing material to be sifted into the region within said skirt, and air-impelling means for producing air currents within said sieve, said air-impelling means having a bottom suction region and a peripheral discharge region, and said rib being below the level of the discharge of the air-impelling means for deflecting particles of material passing downwardly within said skirt to the zone of action of said air-impelling means.

5. A device of the character described, comprising grain-scouring means including an abrasive rotor rotatable on a generally vertical axis and from which grain is outwardly discharged, air-impelling means carried by said rotor and having a bottom suction region, and a tubular sieve extending around said rotor in outwardly spaced relation thereto, said sieve having an annular baffle below the level of the abrasive rotor and the discharge of the air-impelling means to deflect coarse light particles inwardly to the zone of action of said air-impelling means.

6. A device of the character described, comprising grain abrading means including an abrasive rotor rotatable on a generally vertical axis, a laterally shiftable receptacle below said abrading means, a vertical retractable sieve carried by said receptacle and having a tubular upper portion extending around said abrading means, and means for supporting and centering said receptacle with respect to said abrading means.

7. A device of the character described, comprising grain-abrading means including an abrasive rotor rotatable on a generally vertical axis, a laterally shiftable receptacle below said abrading means, a sieve secured to said receptacle and having an upper portion adjacent to said grain-abrading means and retractable downwardly therefrom to permit lateral shifting of said receptacle with said sieve, and means for supporting and centering said receptacle with respect to said abrading means.
